UNITED STATES PATENT OFFICE.

WILLIAM HUGHES BUTTERFIELD, OF BIRMINGHAM, ENGLAND.

DESIGN FOR A CRANK-CASE.

50,057.

Specification for Design.

Patented Dec. 19, 1916.

Application filed August 24, 1914. Serial No. 858,373. Term of patent 14 years.

To all whom it may concern:

Be it known that I, WILLIAM HUGHES BUTTERFIELD, subject of the King of Great Britain, residing at Levis Motor Works, Station Road, Stechford, Birmingham, in the county of Warwick, England, have invented a new, original, and ornamental Design for a Crank-Case, of which the following is a specification, reference being had to the accompanying drawing, forming part thereof.

Figure 1 is a central horizontal section through an article embodying my design.

Fig. 2 is a perspective view showing one face of the article shown in Fig. 1. Fig. 3 is a perspective view of the reverse face of the article shown in Figs. 1 and 2.

I claim:—

The ornamental design for a crank case, as shown.

WILLIAM HUGHES BUTTERFIELD.

Witnesses:

WILLIAM E. JONES,
ELSIE M. WILSON.
